GLENN J. BARRETT, OF GRAND RAPIDS, MICHIGAN, ASSIGNOR TO BARRETT ADDING MACHINE COMPANY, OF GRAND RAPIDS, MICHIGAN.

ROTARY RETARDING MECHANISM FOR ADDING-MACHINES AND LIKE DEVICES.

1,003,414.

Specification of Letters Patent. Patented Sept. 19, 1911.

Application filed May 29, 1911. Serial No. 630,110.

To all whom it may concern:

Be it known that I, GLENN J. BARRETT, a citizen of the United States, residing at Grand Rapids, county of Kent, State of Michigan, have invented certain new and useful Improvements in Rotary Retarding Mechanism for Adding-Machines and Like Devices, of which the following is a specification.

10 My invention relates to rotary retarding mechanism for adding machines and like devices.

15 The object of my invention is to provide a simple and effective structure which is certain in operation.

Objects relating to details and economies of construction will appear from the description to follow.

20 I accomplish the objects of my invention by the devices and means described in the following specification.

The invention is clearly defined and pointed out in the claims.

25 A structure which is sufficiently illustrative of the preferred embodiment of my invention is shown in the accompanying drawing, forming a part of this invention, in which:

30 Figure I is a detail side elevation view of a structure embodying my invention as applied to the operating section of an adding machine. Fig. II is an enlarged detail sectional elevation view (parts being in full lines) taken on a line corresponding to line 35 2-2 of Fig. I, from the right hand thereof, or the rear of the machine. Fig. III is an enlarged detail perspective view of the balance wheel showing the spring clutch and pinion, being a view taken from the right 40 of said wheel, as seen in Fig. II. Fig. IV is an enlarged detail sectional view of the spring clutch drum together with the pinion. Fig. V is a detail sectional view on line 5-5 of Fig. IV.

45 Similar numerals of reference refer to similar parts throughout the several views.

Considering the numbered parts of the drawing, 1 is a portion of the frame of an adding machine, to which is secured a plate 50 2 by suitable screws 3 extending into shouldered pins 4, which support the same in spaced relation from the said frame plate 1. A balance wheel 5, preferably formed of sheet metal, with a weight 6 therein, is carried on a suitable pin 8, which is provided

with journals 7-7 at each end, as clearly appears in Figs. I and III. The periphery of said wheel is smooth and cylindrical to coöperate with a brake shoe. An internal clutch drum or member 9 is journaled on 60 the pin 8 and is reduced in diameter, tapering, at 9' and is provided on its outer end with a pinion 10, which is secured thereto by a suitable square hole or other means, or may be formed integral. A spiral coil 65 clutch spring 11 embraces the internal drum 9, and is secured to pin 12 near the center of wheel 5 by an eye 13. The opposite end of the spring 11 is bent inwardly at 14 and contacts with the reduced portion 9' of the 70 clutch drum 9 at that point. It will be observed therefore, that the pinion 10 with the clutch member 9 is comparatively free to rotate in one direction against slight friction, but when the direction is reversed, owing to 75 the gripping action of the point 14 of the spring 11, the same will be clutched and the pinion 10 will be rigidly coupled to the balance wheel 5. The clutch drum 9 is preferably reduced in diameter at 9 to minimize, 80 the friction as only slight action is required on the direct stroke of the sector. On the return stroke of the sector positive and substantially instantaneous coupling is required.

85 The driving sector 15 of the adding machine is pivoted at 16, and provided with gear teeth 17 which mesh with the pinion 10. This sector is held in and returned to normal position by the spring 18 attached thereto. A brake shoe 19, preferably faced with leather, is carried by the sector and disposed to contact with the periphery of the balance wheel 5, when the machine is at rest, as clearly appears in Fig. I.

90 The relations of the various parts of my device being now clearly understood, I will point out, that in operation the sector is pivoted to reciprocate, and, being in mesh with the pinion 10, will drive the same in 100 either direction. When the sector teeth 17 swing upwardly, as illustrated in Fig. I, the clutch does not act and comparatively free motion against the tension of spring 18 is secured, there being only sufficient friction to give the balance wheel a slight impulse. When the sector is released, however, and permitted to return to the normal position, as the spring 18 acts upon the sector to return it, the sector immediately 105 110

meets with the resistance of the balance wheel 6, owing to the action of the clutch, and in that way the return action of the spring is resisted and an easy action is secured. The clutch acts because this motion tends to wind the spring 11, and the opposite motion tends to release it. When the spring 18 returns the sector to the normal position, it is stopped by the brake shoe 10 contacting with the periphery of the balance wheel 5. This causes the balance wheel to stop and prevents any violent blow due to the action of the spring 18. Any slight tendency of the weighted brake wheel 5 to overthrow does not act upon the sector to cause undue strain, because this motion is in the direction which releases the clutch. It will therefore be seen that a very effective action is secured. Also the slight friction of the spring when the clutch is released and the parts are comparatively free, aside from taking up all slack at the moment of reverse, also reacts on the sector to assist the sector spring in the effective return at the end of the stroke, owing to the method of the balance wheel, and seats the brake with a gentle action avoiding all jar or rebound. I have shown a most effective and simple means for accomplishing this result. I therefore desire to claim the structure I have produced in its specific form on account of its superiority and also desire to claim the same broadly, as I have indicated in the appended claims.

Having thus described my invention, what I claim as new and desire to secure by Letters Patent is:

1. In a rotary braking device for regulating the action of adding machines, the combination of a reciprocating driving means, having a toothed periphery; a balance wheel on a suitably journaled pin; a clutching drum 10 with pinion revolvably mounted on said balance wheel pin, the portion of said drum next the pinion being of reduced diameter; a coiled clutch spring adapted to fit said clutching drum snugly at the end adjacent said pinion, and loosely at its opposite end toward the balance wheel, and connected to said balance wheel; and a brake carried by said reciprocating driving means and disposed to act on the periphery of said balance wheel, when in normal position co-operating substantially as described and for the purpose specified.

2. In a rotary braking device for regulating the action of adding machines, the combination of a reciprocating driving means, having a toothed periphery; a balance wheel on a suitably journaled pin; a clutching drum 10 with pinion revolvably mounted on said balance wheel pin; a coiled clutch spring adapted to fit said clutching drum snugly at the end adjacent said pinion, and loosely at its opposite end toward the bal-

ance wheel, and connected to said balance wheel; and a brake carried by said reciprocating driving means and disposed to act on the periphery of said balance wheel, when in normal position co-operating substantially as described and for the purpose specified.

3. In a rotary braking device for regulating the action of adding machines the combination of a balance wheel secured to a journaled pin; a clutching drum loosely mounted on said pin, one end of which is of less diameter than the other; a clutching coil spring upon said clutching drum one end of which is adapted to fit said drum snugly at the smallest diameter of the latter; connections between the opposite end of said spring and said balance wheel; and a pinion adapted to rotate and drive said drum in both directions, substantially as described.

4. In a rotary braking device for regulating the action of adding machines the combination of a balance wheel secured to a journaled pin; a clutching drum loosely mounted on said pin; a clutching coil spring upon said clutching drum one end of which spring is adapted to fit said drum snugly at one end; connections between the opposite end of said spring and said balance wheel; and a pinion adapted to rotate and drive said drum in both directions, substantially as described.

5. In a rotary braking device for regulating the action of adding machines the combination of a rotary member mounted in suitable bearings; a clutching drum freely mounted concentric with said rotary member; a clutching spring upon said drum one end of which is attached to said rotary member and means for rotating said drum in both directions.

6. In a control device for regulating the action of adding machines having a rotary member, a clutching means, comprising a drum free to rotate in one direction independently of said rotary member, one portion of which drum being of smaller diameter than the other; a spring coiled upon said drum adapted to fit the same snugly at the point of the smallest diameter of the latter; and connection between said spring and said rotary member, substantially as described.

7. In a control device for regulating the action of adding machines having a rotary member, a clutching means comprising a drum free to rotate in one direction independently of said rotary member; a clutching spring upon said drum one end of which spring is adapted to fit said drum snugly; and connections between the other end of said spring and said rotary member, substantially as described.

8. In a braking device for regulating the action of adding machines, the combination

- of a reciprocating toothed sector; a spring to return said sector; a balance wheel with a brake surface; a brake carried by said sector to act on the said balance wheel; a rotatable clutch member actuated by said sector; and a clutch member carried by said balance wheel and in frictional contact with said rotatable member and coöperating with the said rotatable clutch member to positively couple and drive the balance wheel on the return movement of said sector, coacting for the purpose specified.
9. In a braking device for regulating the action of adding machines, the combination of a reciprocating toothed sector; a spring to return said sector; a balance wheel; a rotatable clutch member actuated by said sector; and a clutch member carried by said balance wheel and in frictional contact with said rotatable member and coöperating with the said rotatable clutch member to positively couple and drive the balance wheel on the return movement of said actuating member, coacting as specified.
10. In a braking device for regulating the action of adding machines, the combination of a reciprocating actuating member; a spring to return the same; a balance wheel; a rotatable clutch member connected to be actuated by said reciprocating actuating member; and a clutch member carried by said balance wheel in frictional contact with said rotatable member, coöperating with the said rotatable clutch member to positively couple and drive the balance wheel on the return movement of said actuating member, coacting as specified.

In witness whereof, I have hereunto set my hand and seal in the presence of two witnesses.
